UNITED STATES PATENT OFFICE.

PAUL WAGNER, OF WAUWATOSA, WISCONSIN.

HOISTING SLING.

Application filed April 30, 1923. Serial No. 635,455.

To all whom it may concern:

Be it known that I, PAUL WAGNER, a citizen of the United States, residing at Wauwatosa, county of Milwaukee, and State of Wisconsin, have invented new and useful Improvements in Hoisting Slings, of which the following is a specification.

This invention relates to improvements in slings for engine hoists.

10 It is the object of this invention to produce a cheap, simple sling adapted for ready attachment to an engine for the hoisting thereof and adapted for manipulation, whereby its supporting portion may readily be brought above the centers of gravity of a plurality of different types of engines so that each engine may be maintained in stable equilibrium.

15 It is a further object of this invention to provide a novel fitting for use with such a hoist which will permit of the ready attachment of the hoist to an engine block in the immediate vicinity of the valves without the danger of damage thereto.

20 In the drawings:—

Figure 1 is a side elevation of a sling embodying this invention with its strands manipulated into position for use with one type of engine.

25 Figure 2 is a similar view of the same device showing its strands manipulated into position for use with a different type of engine.

Figure 3 is a plan view of the sling in its 30 Figure 1 adjustment, as it appears when applied to an engine block.

Figure 4 shows the sling in its Figure 2 adjustment applied to a different type of engine block from which the cylinder head 35 has been removed.

Figure 5 is an enlarged detail view in side elevation of the fitting through which the strands of the sling are preferably attached to an engine block, the engine valve and a fragment of the engine block being also shown.

Like parts are identified by the same reference characters throughout the several views.

40 In the preferred embodiment of this invention an annulus or ring 10 provides means through which the sling herein disclosed can be connected with hoisting tackle for lifting an engine. It is desired to lift each engine in such a way that it will be

inherently stable. Engines are ordinarily bolted to their beds and in order not to bend the attaching bolts it is very desirable that the hoist shall be applied to a point approximately above the center of gravity of each 60 engine so that the engine will not only be stable but will remain substantially level during a hoisting operation. I have found that many different types of engines can be supported in the desired manner by a sling 65 having three strands, two of which are of equal length and the third of which is of different length.

I am aware that slings have heretofore been made in which three strands or chains 70 have been used and in which one of the strands has been made in such a manner as to render it adjustable in length. I have made the discovery, however, that I can secure as good results with strands which are 75 non-adjustable and which, therefore, require little time for manipulation and can be used with no danger of slippage or breakage.

In the accompanying drawings I have shown two strands 11 and 12 of equal length 80 and one strand 13 which is shorter than the others. It is immaterial how these strands are made, since they may be so constructed of cable as to be as strong as the chain strands represented in the drawings. 85

Each of the several strands 11, 12 and 13 carries at its end a specially designed fitting 14. This fitting may conveniently comprise a short piece of metal apertured adjacent each end and bent intermediate its ends to an obtuse angle. The apertures 15 are adapted to receive the final link of the chains which comprise the several strands. The apertures 16 are adapted to receive the cap screws or bolts by means of which the engine head is 90 ordinarily bolted to the cylinder block. Any other cap screws or bolts about the engine may also be passed through said apertures to secure the fitting 14 to the engine for hoisting purposes, but the sling is illustrated 95 as being applied to the cylinder head bolts in order to bring out more clearly the reasons for the particular structure of sling herein disclosed.

A cylinder block is shown at 18 in Figures 100 4 and 5. From this cylinder block project screws or bolts 19, by means of which the cylinder head casting is secured to the block. The same nuts 20 which are threaded upon the screws 19 to hold the cylinder head in 116

- place may also be utilized upon said screws to hold fittings 14 in place. Obviously, if cap screws are used in place of screws or bolts 19, such cap screws will provide their own heads, and nuts 20 will be unessential. It is particularly to be noticed that the upwardly bent portion of fitting 14 readily clears the open valve 22 in such a way as to avoid the possibility of injury to said valve.
- 10 At the same time the angularity of the fitting is such that the upwardly bent portion thereof corresponds quite closely to the line of strain through strand 13 which carries it. There is, therefore, little tendency for the fitting to become bent or broken in use.

The engine shown in Figure 4 is intended to represent an engine of a type having a magneto built into the fly-wheel and a planetary transmission. The supporting housing 23 for these parts is ordinarily removed with the engine from the vehicle and constitutes a heavy weight tending to throw the engine proper out of balance on its longitudinal axis. In such an engine of a well known make the cap screws which secure the cylinder head in place are disposed substantially as indicated in Fig. 4 and I have found that such an engine can be very well balanced during its removal if the supporting sling herein disclosed is attached as indicated in Fig. 4. The short strand 13 of the sling is disposed between the other two strands as shown in Fig. 2 and is extended rearwardly. The two outside strands 11 and 12 are extended to opposite sides of the motor and the ring 10 is thereby brought to a position very close to vertical alignment above the center of gravity of the engine.

In the type of engine shown in Fig. 3 the device is substantially balanced but the disposition of the studs or cap screws 19 which secure the cylinder head in place is such that a sling having its several strands of equal length cannot satisfactorily be used to position the annulus or ring 10 above the center of gravity of the engine. I have found, however, that the same sling which operates satisfactorily in connection with the type of engine shown in Fig. 4 can also be utilized

40 to maintain the type of engine shown in Fig. 3 in balance during the hoisting of said engine. It will be noted that the two center bolts 19 at the front of the engine are closer together than the corresponding bolts 45 19 at the far side of the engine as it is viewed in Fig. 3. Accordingly, the two longer strands 11 and 12 are led to the two center bolts which are farthest apart at the rear side of the engine and the shorter strand 13

50 has its fitting 14 secured to one of the center bolts 19 at the front side of the engine. The nearness of this front bolt 19 to the transverse center line of the engine compensates for the shorter length of strand which

55 is led thereto and the ring 10 is thus posi-

tioned substantially above the center of gravity of the engine block.

In order that the several strands 11, 12 and 13 may conveniently be extended into positions in which they are shown in Fig. 3 it is necessary to effect a readjustment of the strands from the position which they occupy when they are used on an engine of the type shown in Fig. 4. This readjustment is clearly illustrated in Figures 1 and 2. Fig. 1 shows the strands in the position in which they are used in Fig. 3 and Fig. 2 shows the strands in the position in which they are used in Fig. 4. The structure illustrated makes the adjustment of the device between its two positions shown in Figs. 1 and 2 an extremely simple matter. It is only necessary to slide strand 11 in a counter-clockwise direction around the ring 10 to change the device from its Fig. 1 position to its Fig. 2 position. Obviously, by the above described manipulation of strand 11 it may be moved from one end of the series of strands to the other end thereof, thus causing the shortest strand 13 to occupy a central position instead of an end position. In the central position of said strand it is best used upon an engine of the type shown in Fig. 4, whereas in the end position of said strand it is best used on an engine of the type shown in Fig. 3.

From the foregoing it will be apparent that although I do not actually change the length of any chain in my device, I am able by an adjustment of a single strand to produce an effect equivalent to a change in length of two strands. The effect produced is equivalent to a lengthening of the end strand of the series and a shortening of the strand adjacent thereto.

It should be further noted with reference to the Fig. 3 construction that the cylinder head is shown to be in place. It is immaterial in the use of this device whether the cylinder head is in place upon the engine or not. The fittings 14 are adapted in either case to receive the cap screws or bolts 19, the primary function of which is to secure the head in place.

The sling here shown may be manipulated with such ease for use under varying circumstances that it is very serviceable for hoisting purposes in any shop where heavy castings are to be lifted. In actual practice, however, the device has been found particularly useful in garage work where the hoisting of different types of engines from motor vehicles is of common occurrence. The particular sling herein disclosed has its longer strands nine and one-half inches in length and its shorter strand 13 is eight and one-half inches long. The measurements are taken from the upper ends of the chains to the apertures 15 in each case.

While I do not wish to limit myself to a

hoist of the dimensions given, I nevertheless wish to make it clear that a sling having these particular dimensions has, in actual practice, proven very valuable for lifting 5 many different types of engines, such as are found in the vehicles most widely distributed.

It is further to be noted that the use of three strands is preferred to the use of any 10 other number of strands. Where three strands are used the engine supported thereby will be in stable equilibrium and the load will ordinarily be divided with substantial 15 equality between the strands. I have found it possible to stand upon any part of an engine supported by a sling of the type disclosed herein without disturbing the equilibrium of said engine.

While the use of a circular frame or annulus 20 is preferred, it will be obvious that the frame 10 might be constructed in other forms to operate with almost equal satisfaction. The principal requirement is that any of the strands such as chain 11 can be 25 manipulated completely around the frame to the opposite end of the series of strands supported therefrom. This result would be almost as easily accomplished if the metal comprising frame 10 were bent to triangular, 30 rectangular or oval form or, in fact, to any other closed or substantially closed figure.

I claim:—

1. A hoisting sling including a frame, and a plurality of strands of differing lengths 35 supported therefrom and adapted for manipulation about said frame, whereby their sequence may be changed.

2. A hoisting sling including a closed frame and three strands freely adjustable about said frame, two of said strands being 40 of substantial equal length and the third strand being shorter than the other two.

3. A hoisting sling including a ring, one relatively short flexible strand and two relatively long flexible strands loosely connected 45 with said ring, and an apertured fitting connected with each of said strands.

4. A hoisting sling including a frame, three flexible strands loosely connected with said frame, and fittings connected with each 50 strand and each comprising an obtusely angled plate provided with an aperture in one portion thereof.

5. A hoisting sling comprising an annulus, a relatively short length of chain 55 having one of its links engaged about said annulus, two relatively longer lengths of chain each having a link engaged about said annulus, and a connecting fitting attached to each of said lengths of chain, each fitting comprising a plate having obtusely related arms each provided with apertures, one of said apertures being disposed to receive a link of the chain to which the plate is 60 attached.

6. An engine hoisting sling including a fitting comprising two apertured arms joined at an obtuse angle, the aperture in one of said arms being adapted to receive a cylinder head bolt and the angle being 65 such that the other of said arms will clear a valve adjacent such a bolt.

PAUL WAGNER.
